METHOD AND APPARATUS FOR STEAMING
LOCOMOTIVESLeland G. Plant, Washington, D. C., assignor to
Direct Steaming Corporation, Chicago, Ill., a
corporation of Illinois

Application September 7, 1942, Serial No. 457,568

10 Claims. (Cl. 122—396)

This invention relates to systems for servicing steam locomotive boilers at stations where they are wholly or partially emptied and refilled. Its purpose is to facilitate the filling and steaming of locomotive boilers by combination and choice of more than one of several methods, as best suited to the occasion.

The present application is a continuation-in-part of my prior application Serial No. 389,999, filed April 23, 1941, containing claims for a specific booster or mixer which embodies structural features not claimed in the present application.

The invention comprises apparatus that can be controlled independently, in relation to each of a group of stored locomotives, to select, at will, the method preferred for filling and steaming each of these locomotives separately. It is applicable to a locomotive terminal operated and equipped according to the invention of Plant 1,686,103 wherein all fires are banished from the house in which the locomotives are stored.

In a terminal of this type, the locomotives have their steamed condition either maintained or restored at storage positions segregated from the locations at which their fires are extinguished on arrival, and at which their fires are later relighted preparatory to departure.

The method that has generally been employed for restoring locomotives to steamed condition at the storage stations in terminals operated as above, is that of Otis 1,592,618 but the operation of a fireless engine storage house, as was first proposed by the present applicant in his invention above cited, does not specify and is not built upon any one method for restreaming locomotive boilers without fire therein. Other practical methods devised to accomplish this operation include that of Miller 1,870,582 and a method practiced in using the apparatus of Phelps 1,927,613.

In the Otis method, the boiler filling operation is accomplished with a supply of heated water and of steam delivered, from separated sources, to the locomotive boiler, through a mixer, at such temperatures and in such proportions that the mixture entering the boiler has a temperature in excess of 212° F. Following the filling operation, live steam alone is supplied to the boiler at a pressure required for building up a working pressure on the locomotive, with water in the boiler at a temperature corresponding to this steam pressure. This method allows steam of any desired pressure to be admitted to the mixer during the filling operation and it is customary to draw steam from the same supply pipe to the

mixer when filling a boiler as later when building up a working pressure in the boiler.

In the Miller method, the boiler filling operation is accomplished with a supply of water under pressure at a temperature slightly below 212° F. and, from a separate source, a supply of steam admitted to the locomotive boiler, in mixed relation to the water, whereto the steam is supplied at a lower pressure than the water. Following this filling operation, the method contemplates supplying additional steam alone, at high pressure until a self-propelling pressure is created in the locomotive boiler. The illustration of this invention shows one mixer for serving a plurality of locomotive stations by means of a main through which the mixture of water and steam is piped. Because of the lower pressure of steam in relation to the water pressure, which is a characteristic claimed for this invention, the steam must be entrained by the water flowing into the main (instead of the water being entrained by steam as practiced by Otis). A separate pipe main serving the same plurality of locomotive stations is shown by Miller for supplying the additional high pressure steam for building up a working pressure in the locomotive boilers.

In the actual use of this method it has been found more practical to provide an individual mixer at each locomotive station but because the steam is entrained by the water in this invention it is necessary to introduce the water through a nozzle into the mixer and direct the steam into a chamber surrounding this nozzle. In this application of the invention the practice to date has been to limit the steam supply to that delivered through the mixer, at a pressure subordinate to the water pressure.

In the procedure for which the apparatus of Phelps was devised, the locomotive boiler is filled with water at steaming temperature supplied from a source in which a body of water is accumulated at said temperature. As in the Miller invention, Phelps proposes supplying additional high pressure steam to the locomotive boiler following the filling operation, to build up a self-propelling pressure therein, and provides a pipe line through which live steam can be delivered directly from the stationary steam supply to the locomotive boiler, at each station.

The present invention provides an apparatus adapted for installation at each of any number of stations where locomotives are stored and serviced. It enables either the Otis or Miller methods for filling and steaming locomotives to be practiced optionally, at any of said stations, by a

manipulation of control valves at the station, preserving the characteristic advantages of each, as best suited to the occasion, in a locomotive terminal adapted for operation according to the Plant method, wherein locomotive fires are banished from the stations at which the locomotives are stored and serviced.

The apparatus of this invention includes a steam and water mixer connected into supplies of steam and heated water, through an arrangement of pipes and valves whereby the relative pressures at which the supplies of steam and heated water are available to the mixer may be reversed, at will, without altering the initial pressures at which the steam and water are delivered from their sources, and maintaining a relation wherein the lower pressure medium is entrained by the higher pressure medium in the mixing process.

In the following drawings of this invention:

Fig. 1 is an elevation representing sources of steam and heated water, in typical relation to the apparatus of this invention, shown partially in section, at a locomotive storage station, where it is connected to a locomotive boiler, here represented by a cross-sectional view through its firebox.

Fig. 2 is a cross-section through an apparatus which is a modification of this invention for altering the paths and relative pressures of water and steam supplied to a locomotive boiler through a mixer of the type shown in Fig. 1.

Fig. 3 is a sectional view through the apparatus of Fig. 2, showing two rotary valves therein, turned at an angle of approximately 90° in relation to the preceding view, for the purpose of altering the paths and relative pressures of steam and water supplied to a locomotive boiler, through the mixer.

Fig. 4 is an elevation representing sources of steam and heated water, in typical relation to a modification in the apparatus of this invention, which here employs a steam valve and throttling pipe, at each storage station, in lieu of a single pressure reducing valve as shown in Fig. 1.

Fig. 5 is a cross-section through the steam and water supply lines of the preceding views, and a distributing valve, which is a modification of the invention, to automatically effect a transposition in the paths of steam and water supplied to and through the mixer, following upon each reversal in the relative pressures at which the steam and water are supplied thereto.

Fig. 6 is a sectional view through the distributing valve of Fig. 5, showing its position, as altered from the preceding view, to accomplish a transposition in the paths of water and steam to and through the mixer, in response to a reversal in the relative pressures of steam and water supplied thereto.

The mixer 15 is typical of a construction commonly used since 1927 adapted to introduce the water through a nozzle 16, from which it emerges into the combining tube 17, at high velocity and there entrains a quantity of steam supplied to the chamber surrounding nozzle 17. The representation of this mixer is diagrammatic and its passages may be so proportioned that when steam alone is supplied to said chamber, it may be introduced at any desired high pressure and will pass on to the locomotive boiler 20, through pipe 19, without appreciable loss in its pressure. These passages may in the same proportioning, be adapted to introduce steam through its nozzle

16, and to receive water in the surrounding chamber from which it is entrained by said steam, when the steam is supplied thereto at a pressure higher than the water pressure, for which optional procedure, the arrangement of valves and pipe connections is provided by modifications of this invention, as shown in Figs. 2, 3, 5 and 6.

In the operation of this invention by means of the apparatus shown in any of the accompanying drawings, the relative pressures of steam and water as supplied to mixer 15, during the filling operation may be reversed, at will, by a manipulation of valves provided at each locomotive storage station, irrespective of the relative pressures at which supplied from their sources 1 and 2, through pipe mains 4 and 6.

In the apparatus of Fig. 1, there is a steam main 4, adapted to deliver high pressure steam direct from its source 1, through individual branch pipes, to each of the mixers 15, of which one only is shown in this view. In this arrangement, there is also a steam main 5, adapted to deliver reduced pressure steam, as fed from source 1, through the pressure reducing valve 10, to each of the mixers 15, through other individual branch pipes. There is also a water main 6, for supplying to each of the mixers 15, water from the source 2, at the pressure with which it is discharged by pump 3. The high and the reduced pressures at which steam is supplied through mains 4 and 5, are respectively above and below the pressure at which water is supplied by pump 3, through main 6.

By first opening valves 8, in the branch connections from steam and water mains 5 and 6, to mixer 15, later closing these valves and opening another valve 8, in the branch connection from main 4, to said mixer, the pressures at which steam is supplied to mixer 15, said mixer, with its outlet duct 19, detachably connecting into the boiler of a locomotive 21, can first serve as an instrument, local to each locomotive storage station, through which said boiler is filled with water and steam according to the Miller method, and later, without altering its duct connection to the boiler, as the instrument through which the locomotive is brought up to a fully steamed condition, with steam alone, supplied from source 1, at a pressure which may considerably exceed the available pressure of water, which procedure is found in the methods of Otis, Phelps, and others.

In lieu of the pressure reducing valve 10, there may be employed the more elaborate mechanism of Brock 1,896,765 in which the steam from a high pressure source would be fed through a steam actuated engine, producing power by the expansion of this steam, from its initial pressure, to a lower pressure, at which it would be released into a pipe main 5, through which it could be delivered at reduced pressure to each of several mixers. The invention of Brock shows both high pressure and moderate pressure steam mains supplying a "booster fitting" into which a water supply main is also connected. In this earlier apparatus, steam could be supplied through these two mains at pressures above and below the pressure of water supplied to the same fitting, as proposed in the present invention.

However, the Brock apparatus bears a different physical relation to the mixer 15, and is employed in a procedure distinct from the Miller method. It does not anticipate the present invention, as disclosed in Fig. 1, because it introduces the water through a "side inlet" to a booster fitting

of "ordinary construction" which implies that the water enters a chamber surrounding the nozzle to which steam from both of the steam mains is introduced through a "top inlet." To practice the filling operation of the Miller method, the water, as he shows, must be discharged from a nozzle surrounded by a chamber filled with steam at a lower pressure than the water, by which it is entrained. It would be impractical in the operation of filling a boiler by the Miller method to obtain the entraining action claimed, if the water is delivered through a "side inlet" to a chamber surrounding a nozzle into which the steam is supplied through a "top inlet," when the pressure of steam thus supplied is less than the pressure of the water by which it is entrained, as claimed in the Miller invention.

In the modification of this invention shown in Figs. 2 and 3, the apparatus is not only capable of reversing the relative pressures at which steam and water are supplied to the mixer 15, but also accomplishes a transposition in the paths of each in passing through the mixer. For this purpose, two rotary, three-way valves 11, are provided in the pipe connections into each mixer 15. One of said rotary valves 11, has a supply pipe branching from the high pressure steam main 4, the other rotary valve 11, is supplied by a branch pipe from the water main 6. The ports of these rotary valves are sized relatively as indicated by the drawings. Each valve 11, has two outlet pipes, one connecting into the nozzle 16, of mixer 15, and the other into the chamber surrounding said nozzle. From the valve 11, which is supplied with steam, the outlet pipe 5, receives steam at a pressure reduced by its passage through a restricted port in said valve, for delivery into the chamber surrounding nozzle 16, in the mixer 15. From the other valve 11, which is supplied with water, the outlet pipe 7, is provided for carrying water to said chamber, at a pressure which can be reduced, if desired, by restricting the port in said valve through which this water is discharged to the pipe 7.

In operating the rotary valves of Figs. 2 and 3, they are turned through an angle of approximately 90°, and at both extremities of said rotation, they present an inlet port registering with its supply pipe, as above referred to. But in these positions only one outlet port in each valve registers with an outlet pipe, the other outlet port being closed against an outer wall of the valve. Each pair of valves 11, may be interlocked by means of rod 50 connecting operating arms 51 and 52 connected to the respective valves so that when one valve is turned to the position shown in Fig. 2, the other will be positioned as shown in this view, and when one of said valves is rotated approximately 90°, as shown in Fig. 3, the other valve will also be rotated to the position shown in this view.

The effect of this apparatus, as shown in Figs. 2 and 3, is to reduce the pressure of water or steam, whichever is discharged into the chamber surrounding nozzle 16, while allowing the full supply main pressure of steam or water, whichever is selected, to flow into said nozzle. This permits the filling operation to be practiced optionally, at each station, according to either the method of Miller or Otis, and, following the filling operation, by closing a valve 8, in the branch pipe from water main 6, and directing the steam flow from main 4, into the nozzle 16, it permits an unrestricted flow of high pressure steam into

the locomotive boiler until a working pressure is developed therein, approximating the pressure of steam at source 1, which may be substantially higher than the pressure of water available at source 2, through pump 3.

The form of this invention disclosed by Fig. 4, is a modification of the arrangement shown in Fig. 1, to the extent that in place of a main 5, through which a plurality of mixers 15, may be supplied with steam at a reduced pressure, which is below the pressure of water supplied through main 6, steam at this reduced pressure is supplied to the chamber surrounding nozzle 16 of mixer 15, through an individual valve and pipe 12, sized to throttle the flow of steam and thus reduce its pressure to less than the pressure at which water is delivered into said nozzle. In the apparatus of Fig. 4, the maximum pressure of water available for filling the boiler, as above, may fall far short of the working steam pressure desired in a locomotive boiler, and this filling operation is supplemented by supplying steam alone, at its source pressure, through the larger pipe to mixer 15, from main 4.

Miller proposes to supplement his filling operation with a supply of high pressure steam separately piped from its source and would provide independent connections from this high pressure main to the locomotive boiler. But, in the practice of this method to date, the expense of providing a separate main for high pressure steam with individual connections at each locomotive storage station, for accomplishing this supplementary steaming operation, has actually restricted use of the Miller method to filling operations limited to the pressure of water available.

The means employed by the present invention for optionally reducing the pressure of steam supplied to mixer 15, is similar to that used by Murray, 1,788,064 but Murray uses this steam throttling device in a different physical relation to the mixer 15, and for a different purpose. In the apparatus of Fig. 4, steam is supplied to the chamber surrounding nozzle 16, and water is delivered to the mixer 15, through said nozzle. The apparatus of Murray is for the maintenance of a steamed condition, at reduced pressure, in locomotive boilers after same have been filled and in Murray the steam, at whatever pressure supplied, is introduced to the mixer 15, through its nozzle 16. It would be impractical to use the arrangement of Murray in filling locomotive boilers by the method of Miller because the introduction of steam through the nozzle 16, at a pressure below the pressure of water supplied to the chamber around said nozzle, in mixer 15, would not lend itself to the entrainment of steam by the water as intended in practice of the Miller method. On the other hand, this modification of the present invention affords a practical device to accomplish results of the Murray invention for maintaining locomotive boilers in steamed condition, at reduced pressure.

In the operation of the device shown in Fig. 5, the steam is drawn from main 4, at the pressure of source 1, and supplied through valve 13, to the differential pressure distributing valve 14. Water is drawn from main 6, at the pressure received from its source 2, through pump 3, and also supplied to the distributing valve 14. By means of valve 13, the steam from main 4, may either be permitted to flow unrestricted into valve 14, at its source pressure, which is above the pressure at which water is delivered to said valve

14, or it may be throttled in passing through valve 13, so as to reach the distributing valve 14, at a pressure which is below said water pressure. In the valve 14, the central plunger, operating in a cylinder of enlarged diameter, will be responsive to whichever, the steam or water, has the higher pressure on admission to 14, and will move to one side or the other, so as to allow the available area of the enlarged central section of the cylinder in which it operates, to be 10 filled at the higher pressure. By this action, a port is automatically uncovered, permitting the higher pressure medium to flow into the nozzle 16, of mixer 15. By this same action of the distributing valve, two plungers of lesser diameter are shifted with the central plunger to which they are linked, as shown, and in so shifting, another port is automatically uncovered, permitting the lower pressure medium to flow into the chamber surrounding nozzle 16, of the mixer 15. This movement of the smaller plungers serves at the same time to automatically block the passage of the lower pressure medium into the nozzle 16, and to block passage of the higher pressure medium into the chamber surrounding said nozzle in the mixer 15.

Fig. 6 is the same mechanism showing the plungers shifted to the position opposite from that disclosed in Fig. 5, which action has been automatically accomplished simply by altering 30 the pressure at which steam is supplied in relation to pressure at which water is supplied. The same action could be effected in principle, by means for altering the water pressure in relation to the steam pressure, and when either the steam or the water is alone supplied, through this mechanism, it will automatically enter the mixer 15, through its nozzle 16. One effect of this mechanism in relation to the invention, of which it is a modification, is to automatically transpose the paths of water and steam used in the filling operation so that whichever medium is supplied at the higher pressure, it will act to entrain the medium supplied at the lower pressure.

In the above, it will be seen that means are made available in a mechanism, local to each storage station, which can be manipulated at a locomotive storage station in such manner as to optionally practice either the method of Otis or of Miller in filling a locomotive boiler, and to follow this phase of operation with a supply of high pressure steam fed through the same mechanism and pipe connections to the locomotive, all by the simple manipulation of control valves at said station. Advantages of the Miller method which have a particularly practical application to the refilling of boilers in the process of reducing concentrates therein, (known as the T. D. S. process) are thus preserved together with convenient means, controllable at individual locomotive stations, for bringing these locomotives up to a steamed condition, at a pressure desirable to the operation of a fireless engine-house in the invention of Plant, which pressure may be substantially in excess of the water pressure used in the Miller phase.

The Miller method is advantageous for refilling boilers which have been partially emptied in the process of reducing concentration of solids in the water, after a run, and while the boiler is still under a considerable pressure of steam, because the higher water pressure specified, by Miller, enables the filling water to be forced into this boiler against the pressure therein, the water thus supplied being heated to a steaming tem-

perature by entrainment of a relatively small quantity of steam before entering the boiler. If a steam supply of sufficient pressure is depended on for refilling the boiler against its internal pressure, an excessive proportion of live steam and relatively small quantity of water is required, representing a thermal waste when there is available a supply of water heated from sources that would otherwise be wasted.

An advantage of other steaming practices which the apparatus of this invention utilizes in combination with the method of Miller, is found in their adaptability to use of a single mixer and duct connection to the locomotive at each storage station, through which locomotive boilers can be filled with mixtures of steam and water of moderate pressure (in which either the steam or water may be supplied at the lower pressure) and later brought to any desired working pressure by the supply of steam alone, through said mixer and locomotive connection. It is not considered desirable, or even practical, to supply heated water from source 2, by means of a pump 3, for filling locomotives through a main 6, at a pressure at all equal to the steam pressure desired in a locomotive boiler without lighting the fire therein, in the practice of the Plant invention, to avoid smoke until after the locomotive is moved out of its storage station house, for which purpose an ample steam pressure is needed in testing auxiliaries (such as air pumps, etc.) and advisable in cold weather when the locomotive may have to sustain a considerable pressure drop in being moved out doors before its fire is lighted.

The advantage of having both the Miller and other methods optionally available in a compact mechanism, operating through a single connection to a locomotive and controllable, individually at each storage station, is obvious.

I claim:

1. In the operation of locomotive storage stations the steps which comprise separately piping to the station a supply of heated water under pressure and a supply of steam under pressure greater than that of the water and sufficient to develop a working pressure in a locomotive boiler when introduced therein, reducing the steam pressure at the station to less than the water pressure, mixing the two at the station by entraining the steam in the water, and delivering the mixture into a locomotive boiler, then shutting off the water supply at the station and delivering steam to the locomotive boiler from said supply without reducing the pressure.

2. In the operation of locomotive storage stations the steps which comprise delivering into a locomotive boiler from separate, single pressure sources, a supply of heated water and a supply of steam in mixed relation, reversing at will at the station the relative pressures of water and steam to be mixed, directing whichever is being supplied at the higher pressure through a nozzle, and introducing the other to a chamber surrounding the nozzle, and entraining the lower pressure medium in the higher pressure medium in passing from the nozzle.

3. At a locomotive storage station, means for delivering into a locomotive boiler, from separate, single pressure sources, a supply of heated water and a supply of steam, in mixed relation; together with means at said station including control valve means for reversing, at will, the relative pressures of water and steam supplies to be mixed, directing whichever is being supplied at the higher pressure, through a nozzle, and

introducing the other to a chamber around said nozzle, from which chamber the lower pressure medium is entrained by the higher pressure medium, as it flows from said nozzle.

4. At a locomotive storage station, a supply of heated water piped to the station at one pressure and a source of steam piped to the station at a lower pressure, means for entraining the lower pressure steam with the higher pressure water and delivering this mixture into a locomotive boiler; together with control means at said station for shutting off these simultaneous supplies of water and steam and delivering to the locomotive boiler a supply of steam, piped separately to the station from said source at a pressure higher than the water supply pressure.

5. At a locomotive storage station, a supply of heated water and a source of steam, piped separately to the station in mains wherein the steam pressure is higher than the water pressure, means at said station for drawing steam from said supply at a pressure below the water supply pressure, means for entraining it with water at supply pressure and means for delivering the mixture into a locomotive boiler; together with control means at said station for shutting off the supplies for this mixture and means for supplying steam only to the boiler from said source at the pressure of steam as piped to the station.

6. At a locomotive storage station, a supply of heated water and a source of steam, each individually piped from separate sources to the station, of which the steam source has a higher pressure than the water supply; means for delivering said supplies into a locomotive boiler; control means adapted to reduce the pressure of steam supplied at said station to less than the water supply pressure; mixing means at said station adapted to combine the water supply with steam at a lower pressure by entraining the steam in the water; and valve means adapted to selectively admit water and steam to such admixture, preceding its delivery to a locomotive boiler, and means to terminate at will the supplies to said admixture and means to supply steam alone to flow from said source, without pressure reduction, into the locomotive boiler.

7. At a locomotive storage station, a supply of heated water and a supply of steam, each individually piped from separate sources, of which the steam source has a higher pressure than the water source; valve means adapted to reduce, at will, the pressure of steam supplied at said station to less than the water supply pressure; dif-

ferential pressure distributing mechanism responsive to the relative pressures determined by said valve means, to direct the higher pressure supply into the nozzle of a mixer, and the lower

5 pressure supply into a chamber surrounding said nozzle, in such manner that the lower pressure medium will be entrained by the higher pressure medium, and the mixture delivered into a locomotive boiler.

10 8. At a locomotive storage station, the apparatus of claim 7, in which valve means can be operated to shut off the water flow from its supply main and cause steam to flow from its supply main, at source pressure, through said differential pressure distributing mechanism and said mixer, into a locomotive boiler.

9. In a locomotive storage system, a source of steam under relatively high pressure sufficient when supplied to a locomotive boiler to render 20 the locomotive operative, a source of heated water under pressure less than that of the steam source, a steam and water mixer, a pipe leading from said mixer to a locomotive boiler, pipe connections from said sources of steam and water to said mixer, means in said pipe connections for selectively supplying relatively high pressure steam and low pressure water or relatively low pressure steam and high pressure water to said mixer at the will of an operator, whereby the 25 water may be entrained in the steam or the steam entrained in the water in passing through said mixer preparatory to delivery to the locomotive boiler, separate means for cutting off the water supply entirely from said mixer, and 30 means for supplying high pressure steam alone from the source to the boiler.

10. A locomotive steaming system comprising a locomotive storage station, a source of heated water under pressure, a source of steam under 40 pressure greater than that of the water and sufficient when supplied to a locomotive boiler to render the same operative, a steam and water mixer having an outlet adapted to be connected to a locomotive boiler, means for supplying water from said water source to said mixer for entraining steam therein, a conduit, including reducing means, for supplying steam from said steam source to said mixer under pressure less than that of the water to be entrained by the water, control means at said station adapted to shut off the water supply, and means for supplying 45 high pressure steam from said source to the locomotive boiler to render the same operative.

LELAND G. PLANT.
